UNITED STATES PATENT OFFICE.

ALFRED ADRIEN TUNNER, OF LEVALLOIS-PERRET, FRANCE.

RACKET FOR TENNIS OR THE LIKE.

1,054,059.

Specification of Letters Patent. Patented Feb. 25, 1918.

Application filed November 8, 1911. Serial No. 858,245.

To all whom it may concern:

Be it known that I, ALFRED ADRIEN TUNNER, a subject of the King of Great Britain, residing at 45 and 47 Rue Vallier, Levallois-Perret, Department of Seine, France, have invented certain new and useful Improvements in Rackets for Tennis or the Like, of which the following is a specification.

The manufacture of tennis rackets requires for the construction of the frame a wood of a special quality and in a predetermined condition of dryness. Nevertheless in spite of the careful observation of these conditions it has not been possible hitherto to give tennis rackets the qualities of rigidity and of resistance to warping which are necessary for them.

In principle the new method of manufacture which forms the object of the present invention consists essentially in forming the frame of the racket in two parts—an external part formed of a single piece together with the connections to the handle, and an internal part formed of a wooden lath of suitable length and width coiled upon itself a certain number of times so as to have a predetermined thickness, this internal frame, of which the coils are united by glue, being itself fixed to the external frame also by gluing. This new method of manufacture presents the following advantages. 1. The frame of the racket can be constructed with wood of any quality. 2. The rigidity of the frame is considerably increased, which makes possible a much stronger and more durable tension of the cords than in rackets of present construction. 3. The prevention of warping, the frame being homogeneous throughout all its length so that the strains are equally distributed. 4. Great facility in mounting the wedge piece, the tendency of which to escape from its place in a drawback in the ordinary construction, whereas in the new method of construction this tendency is favorable inasmuch as the wedge acting in the manner of a buttress increases the adherence between the outer frame of the coils of the curved lath. 5. A greater resistance at the shoulders which are the weak points in the rackets of usual construction.

A construction of the invention is illustrated by way of example in the accompanying drawing.

Figure 1 shows in front elevation a

racket constructed according to the new method of manufacture. Fig. 2 shows a longitudinal section on the axis. Fig. 3 shows separately and in front elevation the internal frame of the racket. Finally, Fig. 4 shows a transverse section in natural size on the line A—A of Fig. 3.

As has been already stated, the frame is formed essentially of two parts preferably of ash wood, the external 1 and the other 2. The external frame 1 consists of a lath of suitable length so as to possess the ends 3 and 4 which form in combination with a piece of wood inserted between them the handle 5, as in the usual construction. Fig. 1 shows that the external frame 1 is cut out to have an increasing thickness, and so that the narrowest part forms the upper half of the circle of the frame, while the wider parts 6 and 7 form the shoulders 75 of the racket and thus impart to it a great strength. Transversely the frame 1 may be of uniform width over all its length, or it may be of a width slightly increasing from the top to the bottom as shown in Fig. 2.

The internal frame 2 which forms the characteristic portion of the new construction, consists of a wooden lath of any suitable kind, cut to a predetermined length admitting of it being coiled upon itself a given number of times so as to possess the thickness requisite to form in combination with the frame 1 a frame of dimensions corresponding to those of the frame of the rackets now used. In Fig. 3 which shows in detail this internal frame, it may be seen that the lath is long enough to admit of having four turns or thicknesses 2¹, 2², 2³, 2⁴. Nevertheless it is obvious that this number has nothing fixed about it and can be made more or less according to the length of the lath. The ends 8 and 9 (Fig. 3) of the lath are trimmed off so as to present no projection when the frame is put together. The racket moreover includes as usual the wedge piece 10 fixed in the usual manner between the handle pieces 3 and 4, the wide upper part of said block pressing against the internal frame 2. Finally each of the parts forming the frame as well as the block are perforated with holes for the passage and the securing of the cords or gut in the usual manner.

It will be obvious that any suitable

method of manufacture may be employed for effecting the assemblage of the constituent parts of the racket constructed as hereinbefore described. Nevertheless by way of example it may be pointed out that the lath forming the interior frame 2 is coiled on itself around a block and that simultaneously the coils will be glued on to the other so that when the coiling is finished the lath 10 forms a rigid whole as shown in Fig. 3, which shows that the enrollment is effected in such a manner that the ends 6 and 9 are situated in the smaller axis of the oval. Moreover the interior frame thus constructed 15 is combined with the external frame 1 to which it is glued and the wedge piece 10 is inter-secured in the space left for it and fixed there by means of screws or otherwise. The racket then undergoes all the operations of finishing usually employed.

As will be seen, the novel method of construction of the racket frame which has been above described is particularly remarkable for giving to the said frame the qualities of resistance and homogeneity which are wanting in the ordinary construction.

It will be obvious that from the esthetic point of view the shoulders of the rackets thus constructed may be provided with 20 bindings α in the manner already in use.

Having now particularly described and ascertained the nature of my said invention and in what manner the same is to be performed, I declare that what I claim is:

35 1. A racket having a frame comprising a shaped frame portion consisting of convolutions of a lath, an outer frame portion in-

closing said first frame portion, and means to secure said portions together.

2. A racket having a frame comprising 40 a shaped frame portion consisting of convolutions of a lath, an outer frame portion inclosing said first frame portion and provided with thickened parts to provide reinforced shoulders for the racket, and means 45 to secure said portions together.

3. A racket having a frame comprising 50 a shaped frame portion consisting of convolutions of a lath, an outer frame portion inclosing said first frame portion and providing handle pieces, means to secure said two frame portions together, and a wedge member arranged between said first frame portion and the handle pieces of the other frame member.

4. A racket having a head including 55 strengthening means for said head comprising a single strip of material wrapped a plurality of times in the form of said head and positioned in said head.

5. Means for strengthening the heads of rackets comprising a strip of material having a plurality of turns in the form of said racket and adapted to be secured inside the head of a racket, the ends of said strip of 60 material being correspondingly tapered and oppositely disposed.

In testimony whereof I have affixed my signature in presence of two witnesses.

ALFRED ADRIEN TUNMER.
